US00D797551S

(12) **United States Design Patent** (10) **Patent No.:** **US D797,551 S**
Chatterton et al. (45) **Date of Patent:** **** Sep. 19, 2017**

(54) **RIGID TRAY**

(71) Applicant: **ConAgra Foods RDM, Inc.**, Omaha, NE (US)

(72) Inventors: **Chadd R. Chatterton**, Kenosha, WI (US); **James W. Clements**, Russellville, AR (US)

(73) Assignee: **ConAgra Foods RDM, Inc.**, Omaha, NE (US)

(**) Term: **14 Years**

(21) Appl. No.: **29/520,752**

(22) Filed: **Mar. 17, 2015**

(51) LOC (10) Cl. **09-03**

(52) U.S. Cl.

USPC **D9/425**; D9/430

(57) **CLAIM**

The ornamental design for a rigid tray, as shown and described.

DESCRIPTION

FIG. 1 is an isometric view of a rigid tray showing our new design.

FIG. 2 is a top view thereof.

FIG. 3 is a bottom view thereof.

FIG. 4 is a side view thereof; and,

FIG. 5 is an end view thereof.

The broken lines shown represent unclaimed subject matter and form no part of the claimed design.

1 Claim, 5 Drawing Sheets
